UNITED STATES PATENT OFFICE

BRUCE E. ROSE, OF PORTERVILLE, CALIFORNIA

OFFSET HARROW

Application filed March 17, 1930. Serial No. 436,416.

This invention relates to disc harrows of what is known as the offset type in which the harrows are arranged as front and rear gangs angularly disposed relative to each other in a plane transversely of the movement of the harrow and the draft means is applied to the front harrow to one side of the longitudinal center line of the gangs. Owing to this arrangement it is very easy to steer the gangs in one direction but almost impossible to successfully steer the same in the opposite direction, as is well known to those who have used harrows of this character. It has therefore been recognized that in order to enable the harrows to turn in said opposite direction it is necessary to "jack-knife" the gangs or temporarily reverse their angle so that the discs will then track in the general direction of the turn to be made. Up to this time this jack-knifing of the gangs has been done by means of manually controlled devices of some kind or another, which must be actuated at just the proper moment to obtain the desired results.

The principal object of my invention is to avoid the need of this manual control device by connecting the gangs to each other and to the draft arm in such a manner that any deviation of the tractor laterally from a straight line toward one particular side (preferably the right side) automatically causes the gangs to jack-knife relative to each other so that the discs assume positions necessary for them to readily turn toward that side; and so that the greater the lateral movement of the tractor the greater will be the jack-knifing action. At the same time the returning of the tractor to its normal line of movement again automatically returns the gangs to their proper working position. As a result of my improved arrangement no attention need be given the implement by the driver of the tractor and he can therefore devote his entire attention to properly steering the machine with the knowledge that the discs are properly tracking at all times.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a top plan view of my improved offset harrow arrangement shown in its normal working position.

Fig. 2 is a similar view showing the jacking action of the harrow gangs as the harrow makes a right-hand turn.

Fig. 3 is a fragmentary cross section on the line 3—3 of Fig. 2.

Referring now more particularly to the characters of reference on the drawings, 1 and 2 denote the transversely extending axles of the front and rear harrow units respectively, both being normally disposed at substantially the same angle and to one side of the normal line of draft D. Each axle has a row of transversely spaced harrow discs 3 mounted thereon, the discs being disposed in reversed or opposed relation to each other as usual.

The opposite end journal boxes of the axles have rigid bars or arms 4 and 5 respectively secured thereto, which bars extend horizontally at right angles to the axles. The bars 4 are nearest the line of draft and the bar of the forward gang has a draft arm 6 pivoted thereon and projecting forwardly therefrom for swivel connection to the draw-head 7 of a tractor in the customary manner. The adjacent ends of the bars 4 of the two gangs are connected by a pair of pivoted toggle links 8 while the adjacent ends of the bars 5 are connected by similar links 9. A cross-bar 10 connects the pairs of links at their points of pivotal connection with each other, the length of the bar 10 being such that one pair of the links is practically folded or jacked while the other pair is extended, and vice-versa.

Since both pairs of links are substantially the same length an opposed jacking and extending action of the links will control the angular setting of the harrow gangs relative to each other, as will be evi-

dent. Since the normal operating position of the harrow is when the gangs are at diverging angles to the line of draft, the links 8 will be the ones normally jack-knifed with such positioning of the gangs. The setting of the discs as the harrow advances along a straight line is such that there is no tendency for the setting of the links to be reversed, and it is of course easy to make a left-hand turn, since the disc axles are more or less radial to the center of turning in that direction.

Said axles however are then obviously wrongly positioned for making a right-hand turn and their angularity must be reversed in order to place such axles substantially radial to the center of a right hand curve or turn if each turn is to be properly made. With my improved harrow this is automatically accomplished by the turning of the tractor, and the consequent lateral swiveling of the draft arm 6 toward the right by the following simple means.

Pivoted in connection with the front harrow gang substantially centrally of its ends is a longitudinally extending lever 11 which is also pivoted onto the cross bar 10 intermediate the ends of the same. The forward end of this lever some distance ahead of its pivotal connection with the front gang is pivotally connected to a transversely extending link 12. This link has a longitudinally adjustable swivel connection with a sleeve 13, which itself is mounted on the draft arm 6 intermediate the ends of the latter for longitudinal adjustment thereon. By reason of this connection it will be seen that when the draft arm swings over toward the right with the turning of the tractor in that direction, the forward portion of the lever 11 will also immediately swing toward the right. The rear end of the lever which is connected to the bar 10 will swing toward the left, pushing the bar 10 laterally relative to the gangs and of course causing the links 8 to be extended and the links 9 to be jack-knifed.

This action of the links, as previously explained, causes the angularity of the disc gangs to be reversed, placing them in position to properly make a right hand turn at the same time as the tractor turns, as shown in Fig. 2.

To cause the rear gang to be always held in a predetermined position relative to the front gang, and to also cause said rear gang to assume the desired radial position when making a right turn, the link 8 of the rear gang has a forward extension 8a and the lever 11 has a rearward and angled extension 11a, rearwardly of its pivotal connection with the bar 10; the outer ends of such extensions being connected by an additional link 14. This ties said rear gang link 8 to the lever 11 in such a manner that said link cannot move, so as to allow the rear gang to assume

a different angular position, without also moving the lever 11. The pairs of links 8 and 9 must therefore move in a definite relationship to each other at all times, thereby insuring a proper and continued alinement of the rear gang relative to the front gang being had, and irrespective of whether the lateral action of the draft arm be large or small.

When the tractor again straightens up, to resume its straight line pulling, the action of the parts as above described is of course immediately reversed until the gangs resume their normal operating positions relative to each other, the link 14 forcing the rear gang into proper position.

By reason of the connections between the draft arm and the link-gangs 8 and 9 the gangs are normally held immovable relative to each other so that there is no play or weaving therebetween. The adjustability of the link 12 with respect to the sleeve 13 enables the angularity of the gangs relative to each other to be altered without moving the draft arm; while the adjustment of the sleeve 13 along the draft arm enables the angularity of the latter and consequently the normal lateral position of the tractor relative to the gangs, to be altered without affecting the angular relation of the gangs.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An offset harrow structure comprising front and rear harrow gangs, a draft arm connected to the front gang, pairs of toggle-links connecting the gangs on opposite sides of the harrow, and means between the draft arm and said links for controlling the folding and extending action of the opposite pairs of links simultaneously with the transverse swinging movement of the draft arm.

2. An offset harrow structure comprising front and rear harrow gangs, a draft arm connected to the front gang, pairs of toggle-links connecting the gangs on opposite sides of the harrow, a bar connecting the pairs of links and arranged to cause one pair to be substantially folded while the other is extended whereby to cause the gangs to be angularly disposed relative to a line projected at right angles to the line of draft, and means between said bar and the draft arm for moving the bar in its longitudinal plane with

the swinging of the draft arm in a transverse plane.

3. An offset harrow structure comprising front and rear harrow gangs, a draft arm connected to the front gang, pairs of toggle-links connecting the gangs on opposite sides of the harrow, a bar connecting the pairs of links and arranged to cause one pair to be substantially folded while the other is extended whereby to cause the gangs to be angularly disposed relative to each other, a lever extending longitudinally of the harrow structure pivoted intermediate its ends onto the front gang and at its rear end onto said bar, and a link connecting the forward end of said lever and the draft arm intermediate its ends.

4. A structure as in claim 3, in which the point of connection of the last named link with the draft arm is adjustable both along the said arm and along the link.

5. A structure as in claim 2, with means between one of the toggle-links of the rear gang and the lever to prevent movement of said link unless the lever moves also.

6. A structure as in claim 1, with means associated with said controlling means for preventing movement of one link without the other links moving simultaneously therewith and in a certain definite direction.

7. A structure as in claim 2, with a forward extension on one rear-gang toggle-link, a rearward extension on the lever, and a link connecting the outer ends of said extensions.

8. An offset harrow comprising a pair of gangs in tandem normally lying at a divergent angle relative to each other when in working position, a laterally swingable draft arm on the front gang, pairs of toggle links connecting the gangs, one pair being substantially folded and the other substantially extended when the gangs are in normal working position, whereby a pull on the draft arm in one direction will act to reverse the relative folded and extended positions of the pairs of toggle links, and thus reverse the angular relation of the gangs.

9. A disc harrow comprising disc gangs in tandem, pairs of toggle links connecting the gangs at spaced points whereby the swinging of one gang horizontally will cause one pair of links to be extended and the other pair folded relative thereto, means to thus swing one gang, and means for maintaining the pairs of links in a predetermined relative position.

10. A disc harrow comprising disc gangs in tandem, and normally lying at a diverging angle relative to each other when in working position, pairs of toggle links connecting the gangs at spaced points whereby the swinging of one gang horizontally will impart movement to the links to change the relative angle of the other gang and means to thus swing one gang.

11. A disc harrow comprising gangs in tandem, pairs of toggle links connecting the gangs on opposite sides of the harrow, means for controlling the folding and extending movement of the links, and means for maintaining the pairs of links in a predetermined relative position.

12. A disc harrow comprising gangs in tandem, a pair of toggle links connecting the gangs at one point and another pair of links connecting the gangs at a point spaced from the first links whereby the swinging of one gang will impart movement to the links to change their relative position, and means to maintain the pairs of links in fixed relative positions.

13. A disc harrow comprising gangs in tandem, a pair of toggle links connecting the gangs at one point and another pair of links connecting the gangs at a point spaced from the first links whereby the swinging of one gang will impart movement to the links to change their relative position, and means connecting the pairs of links whereby movement of one pair will act on the other pair to make such relative movement positive.

14. A disc harrow comprising gangs in tandem, pairs of toggle links connecting the gangs on opposite sides of the harrow, and means for controlling the folding and extending movement of the links.

15. A disc harrow comprising gangs in tandem, pairs of toggle links connecting the gangs on opposite sides of the harrow, a draft element connected to the front gang whereby the harrow may be drawn along and turned to one side or the other, and means for controlling the folding and extending of the links with the turning of the harrow.

16. A disc harrow comprising gangs in tandem, a draft arm connected to the front gang, pairs of toggle links connecting the gangs on opposite sides of the harrow and normally disposed so that the gangs are positioned in diverging relation to each other, and means acting through the links to alter the relative angle of the gangs.

17. A disc harrow comprising gangs in tandem, pairs of toggle links connecting the gangs on opposite sides of the harrow, means applied to one gang to swing the same horizontally, and means actuated by the swinging of one gang for controlling the relative extending and folding action of opposite pairs of links.

18. A disc harrow comprising gangs in tandem, pairs of toggle links connecting the gangs on opposite sides of the harrow, and normally disposed so that the gangs are positioned in angled relation relative to each other, means applied to one gang to swing the same horizontally, and means functioning with the swinging of one gang to act on the links to alter the angle between the gangs.

19. A disc harrow comprising gangs in

tandem, pairs of toggle links of the same length connecting the gangs on opposite sides of the harrow, one pair of links being normally folded while the other pair is extended whereby the gangs are then disposed at an angle to each other, means applied to one gang to swing the same horizontally, and means functioning with the swinging of one gang for reversing the setting of the pairs of links to reverse the relative angularity of the gangs.

In testimony whereof I affix my signature,
BRUCE E. ROSE.
